US00D950589S

(12) **United States Design Patent** (10) Patent No.: **US D950,589 S**
(45) Date of Patent: ** May 3, 2022

(54) **DISPLAY SCREEN OR PORTION THEREOF WITH GRAPHICAL USER INTERFACE**

(71) Applicant: **Apple Inc.**, Cupertino, CA (US)

(72) Inventors: **Edward Chao**, Palo Alto, CA (US); **Kevin Will Chen**, Cupertino, CA (US); **Aurelio Guzmán**, San Jose, CA (US); **Marco Triverio**, San Francisco, CA (US)

(73) Assignee: **Apple Inc.**, Cupertino, CA (US)

(**) Term: **15 Years**

(21) Appl. No.: **29/738,594**

(22) Filed: **Jun. 18, 2020**

(51) LOC (13) Cl. **14-04**

(52) U.S. Cl.

USPC **D14/486**

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
